ARRANGEMENT FOR PROTECTION AGAINST
COLD AND INCLEMENT WEATHER

Jean-Philippe Crouzet, 112 Quai Louis Bleriot,
Paris, France

Filed Mar. 25, 1957, Ser. No. 648,252

Claims priority, application France Dec. 18, 1956
2 Claims. (Cl. 2-205)

My invention has for its object a headgear protecting the wearer against inclement weather and particularly against the cold of the surrounding atmosphere.

My improved arrangement is constituted chiefly by a transparent casing surrounding the head of the wearer and bearing through its open lower opening over the shoulders of the wearer, the upper part of his back and of his chest, while furthermore the front surface of the casing is provided with ports through which the outer air required for breathing purposes enters inside the casing. Such an arrangement forms around the head of the wearer a closed chamber protecting against the wind and enclosing a mass of air the temperature of which is substantially higher than the temperature of the surrounding atmosphere by reason of the heat insulation provided by said casing, the difference in temperature reaching as much as 14 to 19° C.

My improved headgear includes preferably attaching means for securing it in position, and constituted chiefly by two eye-bolts positioned on the rear part of the casing to either side of its vertical plane of symmetry together with two eye-bolts positioned similarly on the front part of the casing so as to allow securing to said eye-bolts the ends of so-called Sandow elastic straps passing underneath the arms of the wearer. I will now describe with further details a preferred embodiment of my invention, reference being made to the accompanying drawing wherein:

FIG. 1 is a lateral elevational view of the arrangement or headgear carried by the wearer.

FIG. 2 is a front elevational view of said headgear.

FIG. 3 is a vertical cross-section through the longitudinal plane of symmetry of said arrangement.

The headgear illustrated is constituted by a casing 1 of transparent elastic material resisting inclement weather, preferably the plastic material sold under the registered trademark Plexiglas. Each time it is to be used, the inner surface of the casing should be coated with a non-fatty anti-moisture preparation. This casing the shape of which is readily apparent from inspection of the drawings has a thickness ranging between 1.5 and 2 millimeters. Its lower open end is bounded by a curve which allows its fitting at 2 over the incurved surface of the user's shoulders, at 3 over his chest and at 4 over the upper surface of his back.

The total height of the arrangement is equal to 41 centimeters, or thereabouts, depending on the size of the wearer's head, the height over the shoulder line being equal approximately to 29 centimeters. The transverse breadth is equal to about 28 cms. and the distance between the front surface and the rear convex part is equal to 31 centimeters or thereabouts.

In the front surface of the casing are provided in a preferred embodiment say fifteen openings distributed in two rows, to wit an upper row of seven openings 5 having a diameter of say 14 millimeters and spaced by 19 mm. from one another and by 56 mm. from the lower front edge of the casing, and a lower row of eight openings 6 having a diameter of 12 mm. also spaced by 19 mm. from one another and located at about 36 mm. above the lower front edge of the casing.

A modification to be worn for scooterists when the

2

scooter is provided with a windshield includes preferably only the lower row of openings.

Four eye-bolts are secured to the lower part of the casing, respectively to the rear section and to the front section of the latter to either side of its vertical plane. These eye-bolts allow securing thereto the hooks 9 for attachment of the so-called Sandow elastic straps 10 which are fitted underneath the wearer's arms so as to hold the headgear in position.

The above-described embodiment is capable of numerous modifications without this unduly widening the scope of the invention as defined in the accompanying claims. Thus it is possible to group the air intake openings and to associate therewith heating means operating on a physical principle such as a hot water radiator or else on a chemical principle. It is also possible to provide the intake openings with means for closing selectively some of them in accordance with the modifications in the outer temperature.

20 What I claim is:

1. A headgear comprising a transparent rigid casing adapted to envelop the wearer's head in spaced relation thereto, the said casing having an open end for insertion of the wearer's head, the edge of said casing at said open end being curved to conform with the shape of the top of a shoulder at both sides and of the chest in front and of the back of the wearer in the rear, and adapted to be supported to maintain said casing spaced from the top, front, rear and left and right sides of the wearer's head, the front and rear sides of said casing being outwardly convex, and the lower portions of said front and rear sides of said casing adjacent the said edge being turned inwardly of said casing and adapted to be directed respectively towards the chest and the back of said wearer, and means adapted to maintain the said edge of said casing in position against the shoulders, chest and back of the wearer.

2. A headgear comprising a transparent rigid casing adapted to envelop the wearer's head in spaced relation thereto, the said casing having an open end for insertion of the wearer's head, the edge of said casing at said open end being curved to conform with the shape of the top of a shoulder at both sides of the chest in front and of the back of the wearer in the rear, and adapted to be supported to maintain said casing spaced from the top, front, rear and left and right sides of the wearer's head, the front and rear sides of said casing being outwardly convex, and the lower portions of said front and rear sides of said casing adjacent the said edge being turned inwardly of said casing and adapted to be directed respectively toward the chest and the back of said wearer, means for venting in the chest-covering portion of the casing, and means adapted to maintain the said edge of said casing in position against the shoulders, chest and back of the wearer.
